UNITED STATES PATENT OFFICE

152,807

DESIGN FOR A FOG LENS

Bernard L. Latousek, Los Angeles, Calif.

Application May 14, 1947, Serial No. 139,035

Term of patent 7 years

(Cl. D48—32)

To all whom it may concern:

Be it known that I, Bernard L. Latousek, a citizen of the United States, residing at Los Angeles, in the county of Los Angeles and State of California, have invented a new, original, and ornamental Design for a Fog Lens, of which the following is a specification, reference being had to the accompanying drawing, forming part thereof.

The dominant features of my design for a fog lens reside in the ornamentation of the inner surface thereof.

In the drawings:

Figure 1 is a front elevational view of a fog lens showing my new design.

Figure 2 is a rear elevational view thereof, and

Figure 3 is a transverse sectional view taken on the line 3—3 of Figure 2.

I claim:

The ornamental design for a fog lens, as shown and described.

BERNARD L. LATOUSEK.
